BELT ATTACHABLE CARTRIDGE CASE

William J. Minneman, Clayton, Ohio, assignor to MTM
Molded Products Company, Dayton, Ohio

Filed June 18, 1973, Ser. No. 370,670

Term of patent 14 years

Int. Cl. D3—02

U.S. Cl. D22—14

FIG-1

FIG-2

FIG-3

FIG-5

FIG-6

FIG-7

FIG-8

FIG-9

FIG. 1 is a rear, top and right side perspective view of a belt attachable cartridge case showing my new design;

FIG. 2 is a front elevational view;

FIG. 3 is a rear elevational view;

FIG. 4 is a top plan view;

FIG. 5 is a bottom plan view;

FIG. 6 is a right side elevational view;

FIG. 7 is a left side elevational view;

FIG. 8 is a view similar to FIG. 1 with the lid in opened position; and

FIG. 9 is a rear, top and right side perspective view of another embodiment of a belt attachable cartridge case showing my new design wherein the case is deeper, the middle belt attachment is modified and the feet have been eliminated.

I claim:

The ornamental design for a belt attachable cartridge case, substantially as shown and described.
